US00D612860S

(12) **United States Design Patent**
Tarara et al.

(10) **Patent No.:** **US D612,860 S**
(b4) **Date of Patent:** **** Mar. 30, 2010**

(54) **GRAPHICAL USER INTERFACE FOR COMPUTER SCREEN**

(75) Inventors: **Jennifer Tarara**, Denver, CO (US); **Hye-Jin Nae**, Santa Monica, CA (US); **Holly Holzhauer**, Los Angeles, CA (US); **Amy Ilyse Rosenthal**, Beverly Hills, CA (US)

(73) Assignee: **Yahoo! Inc.**, Sunnyvale, CA (US)

(**) Term: **14 Years**

(21) Appl. No.: **29/299,268**

(22) Filed: **Dec. 20, 2007**

(51) **LOC (9) Cl.** **32-00**

(52) **U.S. Cl.** **D14/485**

(58) **Field of Classification Search** D14/485-495; 715/224, 235, 246, 700, 716, 718, 719, 727, 715/730, 736, 759, 762, 763, 768, 771, 779, 715/780, 794, 808, 809, 810, 825, 829, 834, 715/841, 843, 845, 861, 864, 866, 867, 962, 715/968, 969, 970, 975, 977; 345/59, 902, 345/960; D19/5; D20/11, 27, 35

(57) **CLAIM**

The ornamental design for a graphical user interface for computer screen, as shown and described.

DESCRIPTION

The sole FIGURE is a front view of our graphical user interface for computer screen showing our new design.

The broken lines showing text, humanoids and a computer screen are included for the purpose of illustrating environment and form no part of the claimed design.
